UNITED STATES PATENT OFFICE.

JOHN LYNCH, OF HARRISBURG, PENNSYLVANIA.

STARCHING-MACHINE.

1,211,197.

Specification of Letters Patent. Patented Jan. 2, 1917.

Application filed July 19, 1915. Serial No. 40,661.

To all whom it may concern:

Be it known that I, JOHN LYNCH, a citizen of the United States, and a resident of Harrisburg, in the county of Dauphin and 5 State of Pennsylvania, have invented certain new and useful Improvements in Starching-Machines, of which the following is a specification.

I have perfected an improvement in laundry machinery; particularly machines for starching clothing and other fabrics after they have been washed and before they are ready to be ironed.

The primary object of my invention is 15 to design a starching machine which is so constructed as to effect the starching uniformly and give the very best possible results.

Other objects of my invention are to provide 20 a starching machine comprising a container for the starching solution, in which is located a kind of frame-work or cradle which mounts a proper number of elements by which the working of the starch into the 25 article to be treated is effected, the elements mentioned being adjustable so as to enable the operation to be performed in the most efficient manner; to incorporate in such machine a rotatable body or drum which coöperates 30 with the elements just referred to in such a manner that the position of the body or drum does not have to be changed at all while the machine is in use, the necessary adjustments being made by changing 35 the positions of other parts of the machine instead; to associate with such drum suitable means for preventing articles clinging to the same when they are ready to be discharged from the machine; and further, to 40 include in such machine a flexible carrier or conveyer, which can easily be regulated, and which is adapted to move the articles to be starched through the machine in such a way as to enable the other parts of the 45 machine to operate with them.

The above and some additional objects and advantages of my invention will appear from the following description taken in connection with the accompanying drawings, and be clearly pointed out in the appended claims.

In this specification I describe the preferred embodiment of my invention; but it is to be understood that changes in the

structure thereof can be made within the 55 scope of the claims, as particularly indicated by variations in the phrasing of the same, without departing from the spirit of my invention.

On the drawings: Figure 1 is a top plan 60 of one form of my starching machine; Fig. 2 is a vertical longitudinal sectional view through the same; and Fig. 3 is a sectional view through the parts of my machine by which the starch is worked into the article 65 to be treated.

On the drawings the same numerals of reference are used to indicate the same parts throughout the several views.

My machine comprises a suitable frame-work 1, having the form of a "cradle," above the middle of which is mounted a hollow body in the form of a drum 2 supported upon an operating shaft 3; and below the cradle is a container or pan 4 in 75 which the starching solution is deposited. Mounted transversely in the cradle 6, some distance above the bottom of the pan 4 and between the same and the drum 2 are a number of working elements in the form of 80 corrugated rollers 5, which act to knead or press the starch into the fibers of the article to be starched as it passes between these rollers and the lower half of the periphery of the drum. The cradle consists 85 of side frames 6 which are united by means of cross-bars or tie-rods 7; and are approximately semi-circular in form, so as to make them correspond substantially with the curvature of the bottom of the container 90 4. Through the pan and between the bottom thereof and the drum 2 runs a flexible carrier 8, which is preferably made of a long strip of chamois cloth having its opposite ends joined together to make an endless band; and this band is looped around 95 the corrugated rollers 5.

The centers of the rollers 5 are arranged on the arc of a circle which is concentric with the drum 2, and these rollers are arranged so that they can be readily adjusted and their pressures toward the periphery of the drum 2 accurately equalized. Heretofore in many cases, the rollers 5 have been affixed in the cradle 1; and any adjustment 100 required had to be obtained by changing the position of the drum 2. Such a plan, however, proves very unsatisfactory in practice;

first, because the shaft 3 is connected to a suitable driving pinion and for that reason it was not possible to change the position of the drum except within certain narrow 5 limits; and second, because even if the position of the drum 2 had been changed the result was always too much pressure either upon the lowermost rolls or uppermost rolls. As a consequence the starching would vary 10 and the performance of the machine was often quite unsatisfactory. I have overcome these defects by mounting the rollers 5 so that their trunnions or journals are received in supporting members or frames 9 which 15 are resiliently supported adjacent the side frames 6 of the cradle 1. Each of the frames 9 will receive the adjacent ends of a set of rollers 5 shown as three in number, and a similar frame will receive the opposite ends 20 of the rollers in the same set on the other side of the machine. The outside rollers of each set are affixed in their frames 9; that is to say, they are not adjustable except by moving the frame 9; but the middle roller of 25 each set is yieldably mounted by providing the two frames connecting it with the central sockets 10 containing curled springs 11, and furnishing journal boxes 12 on the trunnions or journals at the opposite end of this 30 middle roller. These journal boxes are allowed to move toward and from the center of the drum 2 in radial slots in the frames 9; and it will now be seen that these rollers 5 can be moved by the springs 11 toward the 35 drum or forced away from the drum against these springs. Each frame is also provided with a pair of perforated lugs 14 between which is pivotally secured a shank or bolt 15 which passes through a pair of struts 16 40 comprised in the side frames 6. Springs 17 engage these struts and act upon the shanks 15 so as to normally urge them toward the shaft 3, and thereby tend to draw the rollers 5 against the periphery of the drum 2. By 45 means of adjustable nuts 18 on the shanks 15 the tension of the springs 17 can be regulated.

As above set forth the carrier 8 is looped around the rollers 5, passing both between 50 the same and the bottom of the pan 4, and between the same and the drum 2; at one end of the machine it runs over an adjusting roller 19 and a stretching roller 20, both these rollers being at one side of the drum. 55 The carrier 8 also runs over another roller 20' mounted in the top of the cradle 1 at the opposite side of the drum; this roller serves as a wiping roller, to remove from the surface of the article treated by the machine 60 any excess starch which it may contain after it passes out of the pan 4. Beyond the wiping roller at the right of the drum the cradle 1 is provided with arms 21 connected by cross bars or tie rods 22. These arms 21 65 support guide rolls 23 and 24 adjacent to the

wiping roller 20' and a guide roller 25 at the extreme outer end of the arms 21; the carrier 8 passing over the wiping roller 20', the roller 23, the roller 25 and then back again over the roller 24 into the tank; 70 whereby the carrier affords an extension at this end of the machine along which the articles treated in the machine can be borne after passing through the pan 4, and upon which they can very conveniently be delivered to the attendant or operator. 75

The drum 2 has its circumference perforated, as shown in Fig. 2, and over this perforated circumference is placed a wool and chamois cloth covering 26. Upon the drum 80 I loop a plurality of flexible cords 27 which are in contact with the drum over the major portion of its circumference, but spaced therefrom over a portion of the circumference adjacent the wiping roll 20'. The 85 cords 27 are caused to be spaced over the portion of the drum 2 mentioned by means of a guide roller 28 supported above the wiping roller 20' by a pair of adjustably mounted arms 29. The roller 28 may be 90 grooved for each of the cords 27; and the arms 29 will be mounted upon pivot bolts through lugs in the parts 21 of the cradle. By loosening the nuts on these bolts the arms 29 may be revolved up or down and the position of the roller 28 adjusted. 95

The stretching roll 20 at the left of the drum and the wiping roll at the right of the drum are both adjustably mounted by providing bearings 30, which slide in slots 100 toward and from the shaft 3. Each of the bearings is associated with a spring 31 and an adjusting screw 32 which is carried by means of threaded openings in the projections 33 at the side of the cradle. The only 105 difference in the adjusting arrangement between these two rollers is the fact that in the case of the wiping roll the spring is between the screw and the bearing 30, and in the case of the stretching roll the screw engages 110 the bearing 30 directly, and the spring 31 acts upon the opposite side of the bearing and the lug against which the spring abuts. It will be understood, of course, that by turning the adjusting screws 32 at the opposite ends of the stretching and wiping roller, 115 they can be urged toward the drum 2 with greater or less power, and thus vary their effect.

The roller 19 is a tension roll and is provided with bearings 34 which slide in the slotted projection 35. The bearings 34 have internally threaded lugs 36 receiving each a screw bolt 37, which is mounted to turn in bearings 38. The portions of the bolt 37 125 which engage the lugs 36 may be smooth and this bolt may be held against endwise movement in any suitable way; so that when it is turned it will draw the roller 19 up or move it in the opposite direction as desired. This 130

adjusting bolt 37 can conveniently be provided with a milled head 39 to enable it to be more easily turned.

The function of the machine and the operation of the various parts will now be clear. By referring to Fig. 2 it will be seen that the article to be starched is put in at the left between the drum and the carrier 8, and as the drum is rotated in a counter clockwise direction the article is carried down into the starching solution and up over the wiping roller 20' to the extension of the apron which passes over the wiping roll to the end roller 25; and as the article passes upon the extension, the cords 27 prevent it from clinging to the drum and being carried around into the pan 4 a second time. By a slight tension on the article as it is fed into the machine between the drum and the stretching roll any wrinkles in the article can be removed. The starch is agitated by means of scoops 40 on the inside of the drum 2 whereby the starch is kept at all time in the free and thin liquid state necessary for 25 successful operation.

The springs 17 act upon the frames 9 in such a way that the rollers 5 tend to press one section of the carrier against the lower side of the drum, and the other section of the carrier which passes below the rollers 5 will coöperate with the springs 17 and tend to press the rollers in their turn toward the lower side of the drum. By yieldingly mounting the middle roller of each set all 35 of the rollers 5 tend to press against the lower side of the drum with the same intensity; in other words, their pressures are equalized. The tension of the rollers can be regulated by the nuts as above set forth, and 40 the tension on the carrier can be regulated by means of the bolts 37 and to some extent by the screws 32 when the stretching roll and the wiping roll are adjusted. The starch is taken up by the flat cover 26 of the 45 drum by the lower section of the carrier 8; so that when the article is fed between the carrier and the drum a thin film of starch is applied to both sides and this film is worked into the texture of the article by 50 means of the rollers 5. In my machine there is no danger of any buttons being broken or any part of the article being torn under treatment.

The springs 17 and the pivotal connection 55 between the parts 14 and 15 make the frames automatically adjustable, and by using a plurality of these frames arranged in pairs, each pair having three rollers, only part of the rollers, that is the middle one in each 60 group, has to be yieldable and the cost of manufacture is thus reduced.

I wish to emphasize that the adjustments necessary for the proper working of the machine are effected entirely by means of the 65 tension on the carrier 8, and by manipulat-

ing the frames 9 by means of the nuts 18. The upper section of the carrier is capable of exerting a slight lifting force on the drum, and even should the carrier be drawn somewhat tight the proper operation of the machine will not be effected. By obviating the necessity of changing the position of the drum and effecting all adjustments by means of the carrier and corrugated rollers the shaft 3 can remain in mesh with the 75 driving gear at all times and no interruption take place. It is also unnecessary for the operator to wipe off the surplus starch with his hand as the article comes out of the machine; since this is taken care of by the 80 wiping roller at the right adjacent to the extension of the carrier at the end where the machine discharges.

Having described my invention, what I believe to be new, and desire to secure and 85 protect by Letters Patent of the United States is:

1. The combination of a rotatable drum, a cradle in which the drum is carried, supporting members secured to opposite sides of the 90 cradle, and three rollers arranged side by side in said members in position to bear against the face of the drum, one of said rollers being yieldably mounted.

2. The combination of a rotatable drum, a 95 cradle in which the drum is carried, a pair of supporting members resiliently secured to opposite sides of the cradle, and three rollers arranged side by side in said members in position to bear against the face of 100 the drum, one of said rollers being yieldably mounted.

3. The combination of a rotatable drum, a cradle in which the drum is carried, a pair 105 of supporting members pivotally connected to opposite sides of the cradle, and three rollers arranged side by side in said members in position to bear against the face of the drum, one of said rollers being yieldably mounted. 110

4. The combination of a rotatable drum, a cradle in which the drum is carried, a pair of supporting members pivotally and resiliently connected to opposite sides of the 115 cradle, and three rollers arranged side by side in said members in position to bear against the face of the drum, one of said rollers being yieldably mounted.

5. In a starching machine, the combination of a rotatable hollow drum having its 120 ends open, a starch container in which the drum revolves, means for holding articles to be treated in contact with the drum as said articles are passed through the container, and scoops mounted inside the drum and between the open ends thereof for agitating the starch in the container. 125

6. The combination of a rotatable drum, a cradle in which the drum is carried, a plurality of supporting members adjustably 130

connected to each side of the drum, the members on one side being opposite those on the other, and a plurality of rollers mounted side by side in each pair of oppositely disposed members to bear upon the face of the drum, one roller in each pair of said members being yieldable.
